UNITED STATES PATENT OFFICE.

EMERSON P. JENNINGS, OF LEHIGHTON, PENNSYLVANIA.

ROLLER-CARRIAGE FOR PRINTING-PRESSES AND THE LIKE.

1,355,979.

Specification of Letters Patent. Patented Oct. 19, 1920.

Application filed October 27, 1919. Serial No. 333,613.

To all whom it may concern:

Be it known that I, EMERSON P. JENNINGS, a citizen of the United States, residing at Lehighton, in the county of Carbon 5 and State of Pennsylvania, have invented certain new and useful Improvements in Roller-Carriages for Printing-Presses and the like, of which the following is a specification, reference being had therein to the 10 accompanying drawing.

This invention relates to roller carriages for printing presses and the like.

In printing presses of certain kinds the inking rollers revolve about the form bed 15 and inking drum. In order that the rollers may accommodate themselves to the varying radii of the form bed and inking drum, they are yieldably mounted in a revolving carriage. Presses of this type are frequently 20 operated at a very high speed and the rollers are subjected to a very considerable centrifugal action, which tends to move them out of contact with the drum and the form bed. To overcome this centrifugal action 25 strong springs are used, but in the type of carriage heretofore employed, the space was so limited that the springs were necessarily short and stiff and, consequently, they would frequently crystallize and break, thus necessitating the shutting down of the press until new springs could be installed. 30

One object of the invention is to provide a roller carriage of such a character that there will be little tendency on the part of 35 the springs to crystallize and break.

Further objects of the invention are to provide for a roller carriage which will be simple in construction and operation; which will be of light weight; and which can be 40 applied to the press with little or no modification thereof.

Other objects of the invention will appear as the mechanism is described in detail.

In the accompanying drawings Figure 1 45 is a side elevation, partly in section, of a portion of a printing press, showing my invention applied thereto; Fig. 2 is a transverse sectional view of such a press taken on the line 2—2 of Fig. 1; and Figs. 3 and 50 4 are detail views of one of the bearings on the carrier.

In these drawings I have shown the invention as applied to a flat bed and platen press comprising a normally stationary

platens 1, and a form bed 2, mounted for 55 reciprocatory movement in a right line forward and from the platen. Associated with the form bed and traveling therewith is an inking ground 3, which is preferably rigidly secured to the form bed. The inking 60 drum is provided with axial trunnions 4, which are mounted in slide blocks 5, which in turn are slidably mounted in guideways 6 in the side members 7 of the main frame. Reciprocatory movement is imparted to the 65 combined form and inking drum by means of pitmen 8 which connect the trunnions of the drum with a crank wheel or gear 9 which, in the present construction, is driven from a pinion 10 on the shaft 11 of a belt 70 wheel or pulley 12. The particular construction of the press, other than the movement of the combined form bed and inking drum, does not enter into the present invention and need not here be described in 75 detail, as it is a well-known construction and is shown and described in various patents, such, for example, as the Cartwright Patent No. 1069764, of August 12, 1913.

Ink is transferred to the inking drum 80 from a suitable fountain and in a manner not here shown. Suffice it to say that the mechanism for placing the ink on the drum is of such a character that it will not interfere with the revolution of the inking rollers 85 about the drum and the form. In order that the inking rollers may follow the contour of the combined form bed and inking drum and may be held in contact therewith

at all points of their travel over the same, 90 I have mounted the rollers upon a supporting structure which has radial movement relatively to the drum and upon which the rollers are mounted for movement relatively 95 one to the other and to the drum. In this manner I avoid the necessity of employing separate springs for the several rollers, and I am enabled to use relatively long, flexible springs which, while having ample strength 100 to resist the centrifugal action of the rollers and their carriage, are sufficiently flexible to permit the rollers to accommodate themselves to the contour of the combined drum and form bed. In the present construction I have mounted at each end of the 105 drum a carrier which is rotatable about the axis of the drum, and which is here shown in the form of a plate 13 having a bearing

portion 14, which is journaled on an enlarged portion 15 of the trunnion 4, between the slide block and the ends of the drum. These carriers are rotated in unison 5 about the respective trunnions, and this may be accomplished in any desired manner, as by providing each bearing, 14, with a sprocket wheel 16, which is connected by a sprocket chain 17 with a driven part of the 10 press, which will cause the carriers to be rotated in timed relation with the movement of the combined form bed and inking ground. Each carrier, 13, is provided along opposite sides thereof with guideways to 15 receive and slidably support a supporting structure for the inking rollers. In the present construction the carrier plate 13 is provided at each corner with an outwardly extending portion, which is bent upon itself 20 to form a bearing or slideway 18, the bearings being arranged in pairs, and the bearings of each pair being arranged in alignment one with the other so that the two pairs of bearings constitute the two guideways on the opposite sides of the carriage. 25 The supporting structure may take various forms, but that here shown comprises two rods, or bars, 19, slidably mounted in the respective guideways of the carrier, and connected at their outer ends by means of a cross bar 20, which may be rigidly secured to the ends of the rods 19 in any suitable manner. Springs are applied to the supporting structure, or frame, to move the 30 same toward the axis of the drum, and as here shown, relatively long springs 21 are coiled about the rods 19 of each supporting structure, and are confined between the bearings 18, adjacent to the outer end of the 35 supporting structure, and stops, or collars, 22, rigidly secured to the rods. Preferably, these collars are secured to the rods by means of set screws 23, so that they may be adjusted thereon to regulate the tension of 40 the springs.

The several inking rollers are so mounted upon the two supporting structures that they will move therewith as the supporting structure moves radially or circumferentially, of the drum, and will also have movement relatively one to the other, and relatively to the supporting structures. To this end the rollers are preferably carried by members which are movably mounted upon 50 the respective supporting structures, and, as here shown, these members are in the form of curved bars, or yokes, 24, which are pivotally mounted between their ends upon the cross bars 20 of the respective supporting structures, this being accomplished in the present instance by securing the two yokes to a shaft 25, which is journaled in the respective cross bars and extends lengthwise of the drum. The rollers are mounted 55 at the respective ends of these yokes so that,

as the rollers travel about the drum and form bed, the yokes will rock to permit the rollers to follow the contour of the drum and form. In the present construction I have shown four inking rollers, and have arranged two of these at each end of the yokes 24, and in order that the rollers may better follow the contour of the form and drum, I have mounted each pair of rollers upon a pivoted supporting member, or bar, 26. Each supporting member, 26, is preferably pivotally mounted between its ends on the respective yoke 24, and as here shown, each member, 26, is mounted upon the shaft 27, extending parallel to the shaft 25 and mounted in the ends of the two yokes 24. The two rollers of each pair are mounted in the end portions of the respective members 26, so that they will have swinging movement about the axis of the 75 shaft 27. The rollers may be mounted on the supporting members 26 in any suitable manner, but in the present construction the rollers, which are shown at 28, are provided with trunnions, or wheels 29, which are mounted on the roller shafts 30 and are adapted to travel on tracks 31, which are arranged with the respective ends of the drum conforming to the contour of the drum and the form bed, and which serve to support the rollers in proper contact with the inking drum and the form, and to relieve the same of the pressure that would otherwise be exerted thereon by the springs. The supporting members 26 are bifurcated at their 80 ends to receive the wheels 29, and each arm of the bifurcation is provided with a slot 32, to receive the shaft 30 of the inking roller. A pin 33 extends through the two arms of the bifurcation beneath the shaft 30, and serves to retain the shaft within the slot, or bearing, 32. In the present construction I have also shown the shaft 25 as adjustable in length, and have provided the same with a turn buckle 34 for accomplishing this adjustment. 95

The operation of this device will be readily understood from the foregoing description, and it will be apparent that I have provided a roller carriage in which the 100 rollers will be held in constant engagement with the form and drum, and which is of such construction as to permit the use of long flexible springs which will be subjected to a relatively small amount of movement 105 and will not tend to quickly crystallize and break. Further, it will be apparent that I have provided a roller carriage which is very simple in its construction, and in which the rollers can easily accommodate themselves to the varying radii of the form and drum. It will be apparent that, as the carriage travels about the drum, the several rollers will be held in engagement with the periphery thereof, as shown in Fig. 1, until 110

the foremost roller reaches the edge of the form bed. Because of the manner in which the rollers are mounted, this foremost roller can turn from the periphery of the drum 5 onto the form without moving any of the following rollers out of contact with the drum, and as the carriage continues its movement, the other rollers will successively turn the corner from the periphery of the 10 drum to the flat face of the form without being moved out of engagement therewith and without displacing any of the other rollers. I have found that these movements are better accomplished if the axis of 15 the supporting member 26 is arranged slightly off center, and, as here shown, this axis is, in each instance, nearer the inner ends of the supporting members than it is to the outer ends thereof.

20 While I have shown one embodiment of my invention, I wish it to be understood that I do not desire to be limited to the details thereof, as various modifications may occur to a person skilled in the art.

25 Having now fully described my invention, what I claim as new and desire to secure by Letters Patent, is:

1. The combination with a form bed and an inking drum, of a single supporting 30 structure mounted at each end of said drum for rotation about the axis thereof, each supporting structure being capable of movement transversely to the axis of said drum, two groups of inking rollers mounted on 35 said supporting structures for movement therewith, said groups of rollers being connected one to the other and so mounted on said structures that the two groups of rollers will be movable relatively one to the other 40 and the rollers of each group will be movable relatively one to the other to permit them to accommodate themselves to the different radii of the drum and form bed, and springs to resist the outward movement of 45 said supporting structures.

2. The combination with a form bed and an inking drum, of a carrier rotatable about the axis of said drum at each end thereof, a single supporting structure movably mounted 50 on each carrier, a plurality of groups of rollers mounted on said supporting structures for movement therewith and for movement relatively one to the other, and springs acting on said supporting structures to move 55 said rollers toward the axis of said drum.

3. The combination with a form bed and an inking drum, of a single supporting structure mounted at each end of said drum for rotation about the axis thereof, each 60 supporting structure being capable of movement transversely to the axis of said drum, yokes pivotally supported by the respective supporting structures for movement about a common axis, a group of rollers carried by 65 said yoke on each side of said axis, the roll-

ers of each group being movable relatively one to the other, and springs tending to move said yokes toward the axis of said drum.

4. The combination with a form bed and 70 an inking drum, of a carrier rotatable about the axis of said drum at each end thereof, a single supporting structure mounted on each carrier for movement relatively to said drum, yokes pivotally mounted between 75 their ends on the respective supporting structures, and on a common axis, groups of rollers mounted on said yokes on opposite sides of said axis, and springs tending to move said yokes toward the axis of said 80 drum.

5. The combination with a form bed and an inking drum, of a carrier rotatable about the axis of said drum at each end thereof, a supporting structure slidably mounted on 85 each of said carriers for rotatory movement therewith and for movement transversely to the axis of said drum, yokes pivotally mounted on the respective supporting structures on a common axis, groups of rollers 90 carried by said yokes on the respective sides of said axis, the rollers of each group being movable relatively one to the other, and springs acting on said supporting structures to move said yokes toward the axis of said 95 drum.

6. The combination with a form bed and inking drum, of a carrier rotatable about the axis of said drum at each end thereof, a supporting structure movably mounted on 100 each carrier for rotatory movement therewith and for radial movement relatively thereto, yokes pivotally mounted between their ends on the respective supporting structures and on a common axis, roller supporting members pivotally mounted on each yoke on the opposite sides of said axis, rollers mounted on said supporting members at each end thereof, and springs tending to move said yokes toward the axis of said 110 drum.

7. The combination with a form bed and an inking drum, of a carrier rotatable about the axis of said drum at each end thereof and having guideways on the opposite sides 115 of its axis, and a single supporting structure having parts slidably mounted in the guideways of each carrier, springs acting on said structures to move the same transversely to the axis of said drum, yokes pivotally mounted between their ends on the respective supporting structures for movement about a common axis, and rollers supported between said yokes on the opposite sides of 120 said common axis.

8. The combination with a form bed and inking drum, of a carrier plate rotatable about the axis of said drum at each end thereof and having guideways at the four corners thereof, said guideways being ar- 130

ranged in pairs, a supporting frame comprising rods slidably mounted in the respective pairs of guideways of said carrier plate and connected at their outer ends by a transverse bar, a stop secured to each rod of said frame between the respective guideways, and springs coiled about said rods between said stops and those guideways adjacent to said transverse bar, a yoke pivotally mounted on the transverse bar of each supporting frame, said yokes being movable about a common axis, and rollers carried by said yokes.

9. The combination with a form bed and an inking drum, of a carrier rotatable about the axis of said drum at each end thereof, a supporting structure slidably mounted on each carrier, a shaft extending parallel with the axis of said drum and mounted at its ends on the respective supporting structures, yokes mounted on said shaft near the ends thereof, a group of rollers carried by said yokes on each side of said shaft, the rollers of each group being movable relatively one to the other, and springs tending to move said yokes toward the axis of said drum.

10. The combination with a form bed and inking drum, of a carrier rotatable about the axis of said drum at each end thereof, a supporting structure slidably mounted on each carrier, a shaft extending parallel with the axis of said drum and mounted at its ends on the respective supporting structures,

yokes mounted on said shaft between their ends and near the respective ends of said shaft, other shafts extending parallel to the first mentioned shaft and mounted in the ends of said yoke on the opposite sides of said first mentioned shaft, roller carrying members mounted on said last mentioned shafts near the respective yokes, rollers journaled in said roller carrying members, and springs tending to move said yokes toward the axis of said drum.

11. The combination with a form bed and an inking drum having trunnions at the opposite ends thereof, of carriers having bearing portions rotatably mounted on the respective trunnions and having guideways on the opposite sides of said trunnions, means for rotating said carriers in unison, supporting structures slidably mounted in said guideways of the respective carriers, yokes pivotally mounted between their ends on the respective supporting structures for movement about a common axis, a pair of rollers mounted between said yokes on each side of the axis thereof, the rollers of each pair being capable of movement relatively the one to the other, and springs tending to move said yokes toward the axis of said drum.

In testimony whereof I affix my signature hereto.

EMERSON P. JENNINGS.
